SELF LOCKING THREAD SYSTEM

Jakob de Rytter Kielland, Vinderen, near Oslo,
NorwayApplication April 20, 1932, Serial No. 606,498,
and in Norway May 27, 1931

2 Claims. (Cl. 151—14)

The present invention relates to a thread system, which is so formed, that a selflocking action is obtained between the two threaded parts (bolt and nut) when the nut is pulled into engagement 5 with the abutting surface.

The characteristic feature of the present thread system lies in the use in connection with a normally threaded member (bolt or nut) of another cooperating member (nut, bolt) the thread of 10 which is formed by combining two normal threads with different bottom diameter, said threads being axially displaced with regard to each other a fraction of one full pitch of the thread. The profile height of the thread of the latter part will 15 accordingly be reduced with regard to the normal thread profile and one of the inclined side surfaces of the thread will be stepped from the bottom of the deepest thread and upwards.

When the part which is provided with a combined thread of this description is used together 20 with a normally threaded member, the edge of the normal thread during the engagement between the threads and the abutment will be pressed axially from the deepest part of the modified 25 thread over to the step which is formed by the bottom part of the shallower thread, whereby the two threaded members are automatically locked against relative movement.

On the drawing Fig. 1 illustrates the development 30 of the thread system by means of an axial section through the thread. Fig. 2 is an axial section on a smaller scale through a normally threaded bolt and a nut provided with the modified thread.

On Fig. 1 the curve 1 shows the cross section of 35 a normal thread, whereas the curve 2 shows the thread profile after one of the side surfaces of the normal thread has been machined away in accordance with the invention.

The thread profile obtained in this manner is 40 defined by a curve which passes from point 3, which is the deepest point of the normal thread, over an abutment 5 to the point 4, which forms the bottom of the axially displaced shallower thread 45 and from there along the curve 2 to the curve 1 forming the normal thread profile.

The ridge or abutment which is formed at point 5 between the bottoms 3, 4 of the two displaced

threads, may be more or less rounded off in order to not afford too much resistance against the displacement of the thread of the other member of the system from the bottom of the deepest to the bottom of the shallowest thread. The connection 60 between the two thread bottoms will then be formed by a curved surface, which will be inclined somewhat towards the axis of the thread adjacent the bottom of the shallowest thread.

The dotted line 6 indicates the radially and 65 axially displaced normal thread, which forms together with the normal thread 1 the modified thread profile in accordance with the present invention.

From Fig. 2 it will be seen that the bolt 7 is 70 provided with a normal thread of the Whitworth type, whereas the nut 8 is provided with the modified thread which is indicated by the curve 3, 5, 4, 2 on Fig. 1. When the nut 8 is threaded along 75 the bolt and abuts against the fixed surface 9, it will be displaced axially with regard to the bolt until it arrives in the position illustrated on Fig. 2, in which the exterior edge of the normal thread of bolt 7 rests in the stepped part of the modified 80 thread of nut 8. Instead of using a modified 85 thread, the cross section of which is composed of two axially displaced normal threads with different bottom diameter, one may also use 3 or 4 combined normal thread systems, so as to obtain several steps in the bottom of the thread. 85

I claim:

1. In combination with a normal or standard thread bolt, a self-locking nut having a thread the profile of which is formed by the superposition of two normal thread profiles having different bottom diameters and being axially displaced with regard to each other a fraction of a full pitch of the thread whereby a stepped surface is obtained upon one side of the modified thread. 90

2. A nut as claimed in claim 1 in which the connecting surface between the different thread bottoms of the modified thread is formed as a continuous curved surface which is inclined with respect to the axis of the thread adjacent the shallowest thread bottom. 95

100
